SAFETY RAZOR

Original Filed Oct. 9, 1922

INVENTOR.

William C. Edwards, Jr.

UNITED STATES PATENT OFFICE.

WILLIAM C. EDWARDS, JR., OF KANSAS CITY, MISSOURI.

SAFETY RAZOR.

Application filed October 9, 1922, Serial No. 593,359. Renewed May 11, 1925.

To all whom it may concern:

Be it known that I, WILLIAM C. EDWARDS, Jr., a citizen of the United States of America, and a resident of Kansas City, Jackson County, State of Missouri, have invented 5 certain new and useful Improvements in a Safety Razor, of which the preferred embodiment is illustrated in the accompanying drawings, which form a part of this 10 specification.

The invention relates to an improvement in safety razors, such as employ a transversely flexible, double edged blade, and in which the handle is arranged, substantially 15 as in an ordinary razor with a novel means employed for spacing, positioning, flexing and adjusting the blade. Further objects of the invention relate to a predetermined spacing of the guard member from the cap 20 member, and within which predetermined spacing the flexing of the blade is accomplished to adjust the cutting edges to conform to personal preferences of the user, and such as will best accommodate varied 25 growths of beard; to a transverse passage through the razor, for lather and hair so as to eliminate clogging, and facilitate cleansing operations; and to novel combinations and constructions as will be later described.

30 In the drawings, Fig. 1 represents a top plan view of my improved razor at maximum adjustment. Fig. 2 is a plan view of the pivoted handle and forked shank member. Fig. 3 is a plan view of the preferred 35 form of blade. Fig. 4 is a plan view of the inner face of the preferred form of cap or blade support. Fig. 5 is a side view of Fig. 4. Fig. 6 is an end view of Fig. 4. Fig. 7 is an inside plan view of the preferred form 40 of guard plate. Fig. 8 is a sectional view taken along the longitudinal axis 8—8, Fig. 7. Fig. 8^x is a sectional view taken along the line 8—8, Fig. 7 and looking towards a set of guard teeth of the plate. Fig. 9 is a 45 sectional view taken along the line 9—9, Fig. 7; a section if taken along the line 9'—9', Fig. 7 will disclose a similar view. Fig. 10 is a sectional view taken along the line 10—10, Fig. 11. Fig. 11 is a sectional 50 view taken along the longitudinal axis of the razor parts as first assembled, to show the position of the entering forked member just prior to its coaction with the wedge elements

of the guard plate; included in the view are portions of the wedge means and forked shank situated beyond the sectional cut, but essential to a full understanding of the drawing. Fig. 12 is a view similar to that disclosed in Fig. 11, taken however, after the parts have been fully adjusted as in Fig. 1. Fig. 13 is a front end view of Fig. 1. Fig. 14 is a front end view of Fig. 11. Fig. 15 is a rear end view of Fig. 11 ready to receive the forked fulcrum elements disclosed in Fig. 2. Fig. 16 is a cross-sectional view taken along the line 16—16, Fig. 11. Fig. 17 is a cross-sectional view taken along the line 17—17, Fig. 12. Fig. 18 is a cross-sectional view taken along the line 18—18, Fig. 12, the dotted lines indicating travel from a section taken on line 18^x—18^x, Fig. 11 looking in the direction of the arrows. Fig. 19 is a modification of the cap shown in Fig. 4. Fig. 20 is a modification of the forked shank member seen in Fig. 2. Fig. 21 is a modification of the guard, cap and forked elements, and represents a sectional view taken along the longitudinal axis of Fig. 22, being somewhat similar to the view seen in Fig. 11. Fig. 22 is a cross-sectional view taken along the line 22—22, Fig. 21, and looking in the direction of the arrows. Similar numerals of reference indicate corresponding parts throughout all the figures of the drawings.

Referring to the drawings; 23 represents a razor blade having two opposite cutting edges 23', 23''. The preferred form of blade support comprises a cap 24, shaped to flex a blade transversely, being slightly concave transversely on its inner face, and preferably less in width than the blade 23. A plurality of posts or studs, rigid with the cap 24, project from the concave face thereof, being bisected by the longitudinal axis of the cap, and suitably spaced apart for purposes later disclosed. As shown in Fig. 4, the studs are three in number, 25, 26 and 27; each being circular in cross-section. The modification shown in Fig. 19 comprises a cap 24^x, similar to the cap 24, except as to the stud elements provided; in Fig. 19, two prongs are formed on, or punched from the cap 24^x, being properly spaced the one from the other, and suitably situated along the longitudinal axis of the cap above its

concave face. The ends of the prongs 28 and 29 are bent to form head elements 30 and 31, respectively. The head elements of the studs 25, 26 and 27 are grooved as shown at 32, 33 to provide a central web element 34 for each stud; the width of each slot or groove 32 and 33 is of the proper size to accommodate the gauge of metal employed in the fabrication of the guard plate shown in Fig. 7 and later described.

In the assembly and adjustment of my razor, the blade 23 is placed upon the cap 24, the studs 25, 26 and 27 passing through the holes 35, 36 and 37 of the blade; the flat blade is thus positioned so that the cutting edges project beyond the edges 38, 39 of the cap an equal distance.

The guard element comprises a plate next arranged adjacent the blade 23 and in combination with the cap 24. In the preferred form illustrated in Fig. 7, the guard plate 40 is perforated at spaced intervals, bisected by the longitudinal axis 8-8, to form key-hole shaped openings 41, 42 and 43; each opening is substantially circular in shape towards the forward end of the guard plate 40 and is slotted rearwardly therefrom. The circular portions of the openings 41, 42 and 43 are suitably spaced and of the proper size to pass the studs 25, 26 and 27, after which and under a limited forward sliding movement of the guard plate, the central web elements 34 of the studs enter the rearwardly disposed slotted portions of their respective openings. Referring to Fig. 10 it will be seen that the composite cap, blade and guard plate assembly is symmetrical upon either side of the longitudinal axis 44 which bisects the several web and slot elements of the combination. Thus, due to the co-relation of the gauge of the guard plate and width of the slot openings therein to the depth and width of the groove and web elements of the studs, as illustrated, a locking of the guard plate to the cap member occurs to prevent movement of the guard plate either from or towards the cap member. Thus definite fixed gap spacings are provided at 45, 45 between the edges 38, 39 of the cap and the adjacent longitudinal teeth elements 46, 47 of the guard plate; the grooves 32 and 33 lying in a plane parallel to that of the plane of the cap edges 38, 39, and at a predetermined spaced distance therefrom. The flexing or adjustment of the blade edges 23 is accomplished in these gap spacings.

The adjustment and flexing of the blade is secured through a wedge-like force acting between the blade and the guard plate of the above assembled combination. A shank member 48 is pivoted at 49 to a suitable handle 50; for users who do not prefer the pivoted handle of the customary old fashioned razor, the circular finger receptacle 51 will be found acceptable. The member 48 is

slotted along its longitudinal axis and inwardly from its outer end, as at 52 for a predetermined distance, to provide side fork members 53, 54, whose combined width is preferably less than that of the cap 24. The width of the slot 52 is equivalent to, or slightly in excess of the diameter of the several stud elements of the cap 24.

The cap, blade and guard being assembled as in Fig. 15, the forks 53 and 54 are entered between the blade and the guard from the rear, as in Figs. 11, 12 and 15, being arranged on opposite sides of the studs 25, 26 and 27, which serve as guide elements therefor. At the left hand, or forward end of Fig. 7, will be noted two bosses 55 and 56, arranged one on either side of the longitudinal axis of the guard, and having sloping faces, as wedge-like elements inclined from the base of the guard plate. At the rear end of the guard plate, and bisected by the longitudinal axis thereof, is shown a third boss 57, having also a sloping face inclined from the guard plate as a wedge element. The angle of inclination of the several bosses is the same. The length of the slot 52 is such, that as the entering ends 58 and 59 of the respective forks 53, 54 strike the inclined faces of the forward wedges 55, 56, the base 60 of the slot 52 will at the same instant strike the inclined face of the rear wedge 57, and guided by the studs 25, 26 and 27, will under further inward movement, cause the members 53, 54, 48 to slide and rise on the wedge elements 55, 56 and 57, respectively, to a contact with the flat blade 23 as in Fig. 14. The forked members 53, 54 by this wedge action move away from the base of the guard plate 40 towards the cap 24, always, however, maintaining a condition of parallelism towards such parts. The edges 61, 62 constitute fulcrum elements, and by this movement transversely flex the blade 23 through a successive range of adjustable positions, ranging from that of zero flexure shown in Figs. 14 and 16, to that of maximum flexure as indicated in Figs. 13, 17 and 18.

While the gap spacings 45 remain constant the transverse passage indicated by the arrow, Fig. 17 is of variable dimensions, depending upon how far the forked fulcrum elements have moved away from the base of the guard plate in the adjustment. The angle "A" represents the angle included between the plane 63 of the base of the guard plate 40, and the plane of tangency 64 made by the spaced cap and guard in contact with the skin during shaving operations. Since the gap spacings 45 remain constant under all blade flexing conditions, the angle "A" also remains constant. The cutting edge 23' of the blade in Fig. 16 crosses the plane of tangency 64 while at flexed positions intermediate zero and maximum flexure it is approaching nearer and nearer

to the plane of tangency as illustrated in Fig. 17. Thus my razor is held at a constant angle with respect to the skin surface during shaving operations, the blade being 5 flexibly adjusted on the fulcrum elements 61 and 62 behind the teeth of the guard, and in the gap spacings 45 to suit personal preferences, and to best function with the beard of the user.

10 The component elements included in the razor, previously described, are preferably fabricated, stamped and embossed from sheet metal, but other materials or die castings may be employed; my invention is 15 also applicable to razors of others constructions, such, for instance, as the T-head type, but I deem the balance and swing of the ordinary razor, and as retained in the relationship of the parts in the preferred type 20 illustrated, to be far superior and more in keeping with the several and other advantages indicated in the foregoing description of the preferred parts and their functions. In the stamping of the guard plate 25 40, the longitudinal side edges which include the teeth elements 46, 47 are formed substantially V-shaped in section, as disclosed by the drawings.

In the modification disclosed in Fig. 21, 30 the rear boss 57^x of the guard plate was made wider than in Fig. 18, or of the same width as the fourth boss 57^y; the bosses 57^x and 57^y serve as guides for the forked members of the shank 48, the width 35 of the slot in said shank being of the proper width 52^x, Fig. 20 to function with the side elements of said bosses for such purpose. It will be understood that the guard plate 40, Fig. 21 has forward wedge elements equivalent to the wedge elements 55, 56 and which 40 function with the wedge element 57^x in combination with the forked shank member, Fig. 20 for blade flexing purposes in a manner similar to that previously described 45 with reference to the elements shown in Fig. 1. In the fabrication of the bosses 57^x and 57^y, transverse slits were made in the guard plate, each slit being bisected by the longitudinal axis of the guard, and at a 50 predetermined interval apart. To the right of each slit for a distance, as illustrated in Fig. 21, the metal is depressed, so that the respective slits are widened to enable the heads 30 and 31 of the studs 28, 29 to pass 55 between, and thereby engage and lock the guard plate to the cap. Inner portions of the 60 head elements 30 and 31 of the studs engage with the adjacent bosses 57^y, 57^x of the guard to resist separation of the cap and guard 65 after such assembly, both prior to, and after the combination therewith of the forked fulcrum elements 53, 54; and by contact of outer portions of the head elements 30 and 31 against the adjacent base 70 portions of the guard plate as shown in

Fig. 21, the cap and guard lock and position each other at spaced gap distances, such as 45.

Such other modifications may be employed as lie within the scope of the appended claims.

Having fully described my invention, what I now claim as new and desire to secure by Letters Patent is:

1. In a razor, the combination with a 75 flat blade, of a support for the blade arranged to support said blade near its longitudinal edges; a guard plate, studs rigid with the support for positioning said blade intermediate the support and the guard 80 plate; openings through the guard plate to pass the studs and edge portions of said guard plate adjacent said openings arranged to contact outer and inner elements of said studs and to lock and space said 85 guard and support a predetermined distance apart against movement from or towards each other and within which predetermined spacing the blade is transversely 90 flexible.

2. In a razor, the combination with a 95 flat blade, of a transversely curved cap as a support for the blade; a guard plate, studs rigid with the cap for positioning said blade intermediate the cap and the guard 100 plate; openings through the guard plate to pass head elements of said studs and edge portions of said guard plate, adjacent said openings, arranged to contact outer and inner portions of said head elements and to thereby lock and space said guard and support a predetermined distance apart and within which predetermined spacing the 105 blade may be transversely flexed.

3. In combination in a safety razor, a 110 transversely curved blade support having studs projecting from the inner face thereof; a guard member having openings to pass head portions of said studs and edge 115 portions of said guard member, adjacent said openings, arranged to contact outer and inner portions of said stud head elements and thereby lock said guard member to said blade support and provide a transverse passage therebetween.

4. In a razor, a blade support transversely curved on its inner face, studs projecting from said inner face and along the longitudinal axis thereof; a guard plate having openings, in its longitudinal axis, to pass the studs and slotted portions adjacent thereto, within which web and grooved elements of said studs are engageable under a limited sliding movement, to lock said support and guard at a spaced gap distance 120 125 apart.

5. In combination in a safety razor, a transversely curved blade support having studs projecting from the inner face thereof; a guard member having openings to pass 130

- head portions of said studs and edge portions of said guard member, adjacent said openings, so fashioned that under certain limited sliding movements said edge portions will contact and engage with outer and inner portions of said stud head elements and thereby lock said guard member to said blade support and provide a transverse passage therebetween.
10. 6. In a razor, the combination with a flat blade of a support for the blade; a guard plate, studs rigid with the support for positioning said blade intermediate the support and the guard plate; openings through the guard plate to pass the studs and edge portions of said guard plate, adjacent said openings, arranged to contact outer and inner elements of said studs and to lock and space said guard and support a predetermined distance apart and within which spacing the blade is transversely flexible and a transverse passage maintained intermediate the blade and the guard.
7. In a razor, the combination with a detachable blade having opposite longitudinal cutting edges, of a transversely curved rigid cap arranged to support said blade near its cutting edges; studs rigid with the cap for positioning said blade intermediate the cap and guard plate, said guard plate being provided with teeth along its opposite longitudinal edges and having openings in its longitudinal axis to pass head elements of said studs; and edge portions of said guard plate, adjacent said openings, arranged to contact outer and inner elements of said studs and to lock and space said guard plate a predetermined distance from the cap and on the opposite side of the blade, with the teeth of the guard arranged at a spaced interval from the longitudinal edges of the cap, within which established spacing the blade is transversely flexible behind the teeth of the guard but maintaining a transverse passage intermediate the guard plate and the blade.
8. In a razor, a cap member as a blade support transversely concave on its inner face, studs projecting from the concave face of the cap and along the longitudinal axis thereof; a guard plate; a perforated blade arranged on said cap, and positioned by said studs intermediate the cap and the guard plate; said guard plate having key-hole shaped openings, bisected by the longitudinal axis of the guard plate, for passing head elements of said studs, whence under a limited sliding movement slotted portions of said openings are engageable with web and groove elements of said studs to lock said cap and guard plate at a gap spacing apart; and wedge means functioning intermediate said guard and blade for flexing the blade to a desired degree.
11. In a razor, the combination with a blade, of a support for the blade, shaped to flex the blade transversely; a guard plate; means for positioning the blade between the support and the guard and for locking and spacing the support and the guard plate at a predetermined distance apart; and wedge means functioning intermediate the blade and the guard plate and acting upon fulcrum elements arranged near the cutting edges of the blade and on opposite sides of the blade positioning means, whereby a transverse flexing of the blade is accomplished.
12. In a razor, the combination with a perforated, detachable, transversely flexible blade of a transversely curved cap as a support for the blade; a guard, means rigid with the cap and passing through the blade for positioning the blade and for locking the guard to the cap at a predetermined spaced distance therefrom; and means internally expansible intermediate the guard and the blade and acting upon fulcrum elements arranged near the cutting edges of the blade and on opposite sides of the blade positioning means for flexing said blade

through measurable degrees towards and behind longitudinal edge elements of the guard.

13. In a razor, the combination with a detachable, transversely flexible blade having opposite longitudinal cutting edges, of a transversely curved rigid cap arranged to support the blade near its cutting edges; a guard plate provided with teeth along its opposite longitudinal edges, said plate being detachably secured to said cap at a predetermined distance therefrom and on the opposite side of said blade, with its teeth members arranged at a spaced distance from the longitudinal edges of said cap; and fulcrum edge elements, one adjacent each longitudinal edge of the blade and operable by wedge means functioning intermediate the blade and guard and whereby a transverse flexing of the blade is accomplished to draw the cutting edges of said blade towards and behind the teeth of the guard.

14. In a razor, the combination with a detachable transversely flexible blade having opposite longitudinal cutting edges, of a transversely curved rigid cap arranged to support said blade near its cutting edges; a guard plate provided with teeth along its opposite longitudinal edges, said plate being detachably secured to said cap at a predetermined distance therefrom and on the opposite side of the blade, with its teeth members arranged at a spaced distance from the longitudinal edges of the cap; and wedge means functioning intermediate the blade and the guard and whereby a transverse flexing of the blade is accomplished to draw the cutting edges of said blade towards the teeth of the guard through measurable degrees, without however increasing or decreasing the predetermined spacing of the cap from the guard plate.

15. A safety razor comprising a transversely curved cap having studs provided with heads, a blade having perforations to pass the studs, a guard plate having openings and parts integral therewith to receive, engage and lock to said studs whereby a predetermined spaced relationship is obtained between said cap and guard plate and within which spacing and from the inner surface of the guard plate as a base, expansible means is operable to transversely flex said blade upon fulcrum edge elements arranged contiguous the longitudinal cutting edges of the blade, without diminishing or increasing the established spacing of said guard plate from said cap.

16. In a razor, the combination with a perforated detachable blade of a transversely curved cap as a support for the blade, a guard plate, means passing through the blade for positioning the blade and for locking the cap and guard at a suitably spaced distance apart; a shank member de-

tachably arranged adjacent the longitudinal cutting edges of the blade and intermediate the blade and the guard and extending beyond one end of the above combination.

17. In a razor, a holder comprising a transversely curved cap, a guard, a perforated blade intermediate said cap and guard, positioning means integral with said cap passing through perforations of the blade and detachably engaging with integral elements of said guard to secure said guard at a predetermined spaced distance from said cap; and a shank member having fulcrum edge elements arranged adjacent the longitudinal cutting edges of said blade and detachably engaging intermediate the guard and blade and laterally projecting beyond one end of said combination.

18. In a razor, a holder comprising a transversely curved cap, a guard, a perforated blade intermediate the cap and guard; blade positioning means rigid with the cap, passing through perforations in the blade, and detachably engaging with integral elements of the guard to lock said guard at a predetermined gap spacing from the cap; and a shank member, slotted at one end intermediate fulcrum edge elements, detachably engaging on either side of the blade positioning means intermediate the guard and the blade, and with the fulcrum edge elements arranged adjacent the longitudinal cutting edges of the blade; the opposite end of said shank member projecting beyond one end of said combination as a handle support.

19. In a razor, a holder comprising a transversely curved cap, a guard, a perforated blade intermediate said cap and guard, positioning means integral with said cap passing through the perforations of the blade and detachably engaging with integral elements of said guard to lock said guard at a predetermined spaced distance from said cap, a handle arranged at one end of said holder and pivotally mounted to a shank member, said shank member detachably engaging intermediate the guard and the blade and on opposite sides of said blade positioning means.

20. In a razor, the combination with a perforated detachable blade of a transversely curved cap as a support for the blade, a guard plate, means integral with the cap passing through said blade for positioning the blade, said means engaging to means integral with said guard plate for locking said cap and guard at a suitably spaced distance apart; a shank member detachably arranged on opposite sides of said blade positioning means and intermediate said blade and guard and extending beyond one end of the above combination and a handle pivotally carried by the extended shank portion.

21. In a safety razor, a guard member having teeth elements arranged along its opposite longitudinal edges, a blade supporting cap adapted to flex a blade transversely, means integral with the cap engaging elements integral with the guard member whereby the longitudinal edges of the cap are set at fixed gap spacings from the teeth elements of the guard member; a blade positioned between the cap and the guard member with its opposite cutting edges projecting beyond the longitudinal edges of the cap and over the gap spaces; and fulcrum edge elements, one adjacent each longitudinal edge of the cap and arranged upon the guard side of the blade, adjustably operable from or towards the guard and to cooperate with the cap to flex the edges of said blade in said gap spaces behind the teeth elements of the guard. 70
22. A safety razor comprising a transversely flexible blade having opposite longitudinal cutting edges in combination with a plate having a row of teeth along each of its opposite longitudinal edges as a double guard; a member, longitudinally arranged intermediate the blade and the guard plate and supporting the blade from contact with said guard plate; means for positioning the blade with its cutting edges extending beyond the longitudinal edges of the longitudinal member and adjacent the teeth of the guard plate, the opposite longitudinal edges of said member comprising fulcrum elements arranged upon opposite sides of the blade positioning means; means for adjustably spacing the longitudinal member from or towards the guard plate and in parallelism therewith to provide a transverse passage of variable dimensions therebetween and means for adjustably flexing the blade upon the fulcrum edges of the longitudinal member towards the teeth of the guard. 75
23. In a razor, the combination with a perforated, detachable, transversely-flexible blade of a transversely curved cap as a support for the blade, a guard plate, means rigid with the cap and passing through the blade and engaging to elements integral with the guard plate for positioning the blade and locking the guard to the cap at a predetermined distance apart; and means internally operating on opposite sides of the blade positioning means contiguous the cutting edges of the blade and intermediate the guard and blade for flexing said blade without affecting the spaced relationship of the guard to the cap; and a shank member externally projecting from one end of the combination. 80
24. In a safety razor, in combination, a cap transversely concave on its inner face, a guard plate rigidly positioned at a spaced distance therefrom to provide a transverse passage therebetween, a flat blade arranged intermediate said cap and guard, a shank member laterally projecting from one end of said combination having its inner end forked and arranged intermediate the guard and blade; and wedge-like portions on the inner face of the guard whereby desired inward sliding movements of said shank member occasion a functional relationship of said forked elements with said wedge elements and whereby the blade is flexible to desired positions without affecting the spaced relationship of the cap to the guard. 85
25. A safety razor comprising a transversely flexible blade having opposite longitudinal cutting edges, in combination with a plate having a row of teeth along each of its opposite longitudinal edges as a double guard; a member, longitudinally arranged intermediate the blade and the guard and supporting the blade from contact with said guard; means for positioning the blade with its cutting edges extending beyond the longitudinal edges of the longitudinal member and adjacent the teeth of the guard plate, the opposite longitudinal edges of said member comprising fulcrum elements arranged upon opposite sides of the blade positioning means; a transversely curved blade support secured to said guard plate at a predetermined spaced distance apart by said blade positioning means, said curved blade support overhanging the fulcrum edge elements with its longitudinal edges arranged behind the corresponding cutting edges of the blade and on the side of the blade opposite the said longitudinal member; and means for adjustably moving the longitudinal member away from the guard plate towards the curved blade support to provide a transverse passage of variable dimensions intermediate the longitudinal member and the guard plate and for adjusting and flexing the blade on the fulcrum edges of the longitudinal member towards the teeth of the guard. 90
26. In a safety razor, in combination, a cap transversely concave on its inner face, a guard plate rigidly positioned at a spaced distance therefrom to provide a transverse passage therebetween; a flat blade arranged intermediate said cap and guard, a shank member laterally projecting from one end of said combination having its inner end forked and arranged intermediate the guard and blade; and wedge-like portions on the inner face of the guard whereby desired inward sliding movements of said shank member occasion a functional relationship of said forked elements with said wedge elements and whereby the blade is flexible to desired positions without affecting the spaced relationship of the cap to the guard. 95
27. In a razor, a holder comprising a transversely curved cap, a guard, a perforated blade intermediate said cap and guard, positioning means rigid with the cap pass- 100

ing through perforations of the blade and detachably engaging with said guard at a spaced distance from the cap; wedge-like elements on the inner face of the guard, a shank member arranged intermediate the blade and the guard with one end outwardly projecting therefrom and a functional relationship of said shank member to said wedge-like elements operating to flex said blade to a desired degree.

28. In a razor, a holder comprising a transversely curved cap, a guard, a perforated blade intermediate said cap and guard, stud members rigid with said cap passing through perforations of the blade and engaging with said guard to position said cap and guard at a spaced distance apart; wedge-like embossed portions on the inner face of said guard, a shank member slidably insertable through one end of the combination to a sliding contact with said wedge portions and creating a progressive applied force upon said blade to transversely flex same to a desired position.

29. In a razor, a holder comprising a transversely curved cap, a guard, a perforated blade intermediate said cap and guard, positioning means rigid with said cap passing through perforations of the blade and detachably engaging with said guard at a spaced distance from said cap; wedge-like elements on the inner face of said guard, a shank member arranged intermediate the blade and guard with one end outwardly projecting therefrom and a functional relationship of said shank member to said wedge-like elements operating to flex said blade to a desired degree; and a transverse passage intermediate the shank portion and the guard.

30. In a razor, a holder comprising a transversely curved cap, a guard having teeth along its opposite longitudinal edges, a perforated blade intermediate said cap and guard; stud members rigid with said cap passing through perforations of the blade, openings in the guard, and within which openings said stud members are engageable to lock said guard and cap at a fixed distance apart; a shank member forked at one end, said forks slidably engaging on opposite sides of said studs intermediate the blade and the guard; and wedge-like elements on said guard functioning to lift the forked shank member, in parallelism, from its original position under a sliding movement of said shank member and create an expansible force intermediate the guard and blade, and whereby said blade may be transversely flexed throughout its length in a desired degree.

31. In a razor, a cap member as a blade support transversely concave on its inner face, studs projecting from the concave face of the cap, and along the longitudinal axis

thereof; a guard plate; a perforated blade arranged on said cap, and positioned by said studs intermediate the cap and the guard plate; said guard plate having key-hole shaped openings, bisected by the longitudinal axis of the guard plate, for passing head elements of said studs, whence under a limited sliding movement, slotted portions of said openings are engageable with web and groove elements of said studs to lock said cap and guard plate at a gap spacing apart; and a shank member arranged at one end of the combination and slidably engageable intermediate the blade and guard.

32. In a razor, a holder comprising a transversely curved cap, a guard plate having teeth along its opposite longitudinal edges, a perforated double edged blade intermediate the cap and guard; stud members rigid with the cap passing through perforations of the blade; said guard plate having key-hole openings, bisected by the longitudinal axis of the guard plate, for passing head elements of the studs, whence under a limited sliding movement slotted portions of said openings are engageable with web and groove elements of said studs to lock said cap and guard plate at a gap spacing apart; wedge-like elements on the inner face of the guard member near the forward and rear ends thereof; a shank member, forked at one end and inwardly insertable intermediate the blade and the guard; said forks slidably engaging on opposite sides of said studs, and under further inward movement, and by reason of a contact then made by said forked members with the inclined faces of said wedge-like elements, occasioning a wedge-like force operating intermediate said blade and guard, and whereby the edges of said blade are drawn towards the teeth of the guard in any desired degree, without increasing or diminishing the spaced relationship of said guard to the cap.

33. In a safety razor, a holder comprising a transversely curved cap, a guard plate having a row of teeth along each of its longitudinal edges, a perforated, transversely-flexible double edged blade intermediate said cap and guard plate; stud members projecting from the inner face of said cap and along the longitudinal axis thereof, and passing through perforations in the blade to position its cutting edges behind the teeth of the guard and beyond the longitudinal edges of the cap; said guard plate having key-hole shaped openings, bisected by the longitudinal axis of the guard plate, for passing head elements of said studs, whence under a limited sliding movement slotted portions of said openings are engageable with web and groove elements of said studs to lock said cap and guard plate at a gap spacing apart; wedge-

like elements on the inner face of the guard plate near the forward and rear ends thereof; a shank member, forked at its inner end, narrower in width than the cap, and 5 a handle element at the opposite end thereof; the forks of said member slidably engaging on opposite sides of said studs and intermediate the guard and the blade under an inward lateral movement, and under a 10 further inward movement, and by reason of a progressively moving contact then made by said forked shank with the inclined faces of the wedge-like elements, occasioning a force operating to move the forked shank 15 member, in parallelism, away from the guard plate towards the cap to provide a transverse passage of progressively changing dimensions intermediate the forked shank member and the guard plate, and for adjusting and flexing the blade on outer fulcrum edge elements of said forked shank member towards the teeth of the guard plate. 20

34. A guard member for safety razors 25 having a row of teeth arranged along each of its longitudinal edges; a pair of wedge-like elements projecting from one face of the member near the forward end thereof and arranged one on either side of the longitudinal axis of the member; and a single wedge-like element, bisected by said longitudinal axis, projecting from the same face of the member and near the rear end thereof. 30

35. A guard plate for safety razors having a row of teeth arranged along each of its longitudinal edges and openings in its longitudinal axis; a pair of wedge-like elements projecting from one face of the 40 plate near one end thereof, arranged one on either side of said axis, and a single wedge-like element bisected by said axis and arranged on the same face near the opposite end thereof.

36. A guard plate for safety razors having a row of teeth arranged along each of its longitudinal edges; a plurality of openings arranged at spaced distances apart, bisected by the longitudinal axis of the guard plate, 50 each opening being rearwardly slotted; a pair of wedge-like elements projecting from one face of the plate near one end thereof, arranged one on either side of said axis, and a single wedge-like element bisected by said axis and arranged on the same face of the plate near the opposite end thereof. 55

37. In combination in a safety razor, a guard plate and a shank member having a forked end; said guard plate having teeth arranged along its longitudinal edges, a pair of wedge-like elements projecting from one face of the plate near the forward end thereof, arranged one on either side of the longitudinal axis of said plate, and 60 a third wedge-like element bisected by said

axis and arranged on the same face of the plate near the rear end thereof; the forked end of said shank being slidably arrangeable on said plate and on either side of said third wedge-like portion, and with its opposite end laterally extending beyond the rear end of said guard plate; further inward movement of said shank member upon said plate, causing the forward and rear portions of the forked member to function with said wedge-like portions to raise said shank member from said plate and in parallelism therewith. 70

38. In a razor, the combination with a detachable blade having opposite longitudinal cutting edges, of a transversely curved rigid cap arranged to support said blade near its cutting edges; a guard plate provided with teeth along its opposite longitudinal edges, said plate being detachably locked to said cap at a predetermined distance therefrom and on the opposite side of said blade, with its teeth members arranged at an established spaced distance from the longitudinal edges of said cap; the angle formed between the plane, tangent to a row of teeth of the guard and the adjacent longitudinal edge of the cap, and the plane of the base remaining constant at all times; and within which established spacing between the cap and guard plate, the said blade is transversely flexible to draw the adjacent cutting edge of the blade nearer and nearer to the first mentioned plane of tangency. 90

39. In a razor, a blade support transversely concave on its inner face, studs projecting therefrom and along the longitudinal axis thereof; a guard member having key-hole shaped openings, in its longitudinal axis, for passing head elements of said studs, whence under a limited sliding movement, slotted portions of said openings are engageable with web and groove elements of said studs; and V-shaped longitudinal edge elements of said guard member locked thereby at a spaced gap distance from the longitudinal edges of the blade support. 100

40. In a razor, a blade support transversely concave on its inner face, studs projecting therefrom, and bisected by the longitudinal axis thereof; a guard plate having openings bisected by its longitudinal axis, and within which head elements of said studs are engageable, and V-shaped longitudinal edge elements of said guard plate locked thereby at a spaced gap distance from the longitudinal edges of the blade support; a flat flexible blade positioned by said studs intermediate the blade support and the guard plate, with its longitudinal edges bisecting the planes tangent to the teeth of the guard and the edges of the blade support; a member narrower than the blade support, longitudinally arranged intermediate the blade and the guard plate, and 110

means for adjustably raising said member away from the guard plate and towards the blade support, and to transversely flex the blade upon longitudinal fulcrum edge elements of said member towards said planes of tangency.

41. In a safety razor, a guard member having V-shaped teeth elements arranged along the opposite longitudinal edges; a blade supporting cap shaped to flex a blade transversely; studs rigid with the cap, having web and groove portions engaging slotted openings in said guard plate whereby the longitudinal edges of the cap are set at fixed gap spacings from the teeth elements of the guard member; a blade positioned by said studs between the cap and the guard member with its opposite cutting edges projecting beyond the longitudinal edges of the cap and over the gap spaces; a shank member, forked at one end to provide parallel longitudinally extending fulcrum edge elements and a slot of constant width intermediate said fulcrum elements; said forks slidably engaging on opposite sides of said studs intermediate the blade and the guard member, and with the edges of the cap member overhanging said fulcrum edge elements; and wedge-like elements on the guard plate functioning, under sliding movements of the forked member, to lift said forked member through successive parallel positions and create an expansible force intermediate the guard member and the blade to flex the edges of the blade on said fulcrum edges and in said gap spaces behind the teeth of the guard member.

42. In a razor, a blade support transversely concave on its inner face, studs projecting therefrom and along the longitudinal axis thereof; a guard plate having openings bisected by its longitudinal axis and within which head elements on said studs are engageable and V-shaped longitudinal edge elements of said guard plate locked thereby at a spaced gap distance

from the longitudinal edges of the blade support; a flat, perforated, flexible blade positioned by said studs intermediate the blade support and the guard plate. 50

43. In a safety razor, a guard member having teeth elements arranged along the opposite longitudinal edges, a blade supporting cap shaped to flex a blade transversely, means integral with the cap engaging elements integral with the guard member whereby the longitudinal edges of the cap are set at fixed gap spacings from the teeth elements of the guard member; a blade positioned between the cap and the guard member with its opposite cutting edges projecting beyond the longitudinal edges of the cap and over the gap spaces; a shank member forked at one end to provide parallel, longitudinally extending fulcrum edge elements and a slot of constant width intermediate said fulcrum elements; guide elements in the longitudinal axis of the razor cooperating with said slot, said forks slidably engaging on opposite sides 70 of said guide elements with the fulcrum edge elements arranged, one adjacent each longitudinal edge of the cap and intermediate the blade and the guard member; and wedge-like elements on the guard 75 member functioning, under sliding movements of the forked member, to lift said forked member through successive parallel positions and create an expansible force intermediate the guard member and the 80 blade to flex the edges of the blade on said fulcrum edges and in said gap spaces behind the teeth of the guard member.

44. In a safety razor, a longitudinally extending shank member having a handle element at one end thereof, the opposite end being inwardly slotted along the longitudinal axis thereof for a desired distance to form forked side elements, the outer edge elements whereof constituting fulcrum elements. 85
